UNITED STATES PATENT OFFICE

JESSE L. BRIGHT, OF CICERO, ILLINOIS, ASSIGNEE TO CROWN STOVE WORKS, OF CICERO, ILLINOIS, A CORPORATION OF ILLINOIS

HEATER

Application filed June 29, 1932. Serial No. 618,986.

The main objects of this invention are to provide an improved form of space heater; to provide a space heater having an improved form of radiator; to provide a heater of this kind which is adapted to be placed in the bake oven of an ordinary gas stove for use in heating a kitchen or other rooms particularly when it is desired to quickly heat such rooms without operating the usual central heating plant; to provide improved means for slidably supporting said heater in the gas stove oven; to provide improved means for controlling the flow of air to the heater; and to provide a portable unit of this kind which can be easily inserted into and removed from the stove oven.

Illustrative embodiments of this invention are shown in the accompanying drawings, wherein:

20 Figure 1 is a vertical section of a gas stove oven, showing one of the improved heaters supported therein, the view being taken on the line 1—1 of Fig. 2.

25 Fig. 2 is a horizontal section taken on the line 2—2 of Fig. 1.

Fig. 3 is a vertical section, taken on the line 3—3 of Fig. 2.

Fig. 4 is a perspective of the radiator.

30 Fig. 5 is a horizontal section of a modified form of radiator.

Fig. 6 is a perspective of the removable plate which is placed above the burner when the radiator is removed.

35 Fig. 7 is a section, taken on the line 7—7 of Fig. 2, showing the valve for controlling the admission of air to the oven.

Inasmuch as this improved heater may be used in connection with many different types of stoves, the accompanying drawings show only such parts of a stove as will be helpful in apprehending the invention.

40 In the form shown, the heater is inserted in the oven of a gas stove comprising the usual burner top 1, side walls 2, top 3, rear wall 4, and a front frame 5 having an opening 6 for the bake oven 7, and an opening 8 for the broiler compartment 9. A hinged door 10 is mounted on the frame 5 for closing the opening 6. The broiler compartment 50 may be provided with a drawer similar to that shown in Patent No. 1,885,212 issued June 28, 1932, to Rogers and Rogers.

45 The bake oven and broiler compartment are separated by a shelf 11 supported on a pair of inner removable linings 12 which are sus-

pended in spaced relation to the side walls. The linings 12 are provided with the usual racks 12A for supporting the usual adjustable shelves, not shown. Mounted directly below the shelf 11, is the usual burner 13. Formed in the shelf 11 is a central opening 14, which is adapted to be covered by a removable plate 15 when the heater is removed and the oven is used for baking. This cover has a hollow portion 16 adapted to fit within the opening 14.

50 Flues 17 at the sides of the oven, provide communication between the broiler compartment and the upper part of the bake oven. At the top of the bake oven is a lining 18 which is spaced from the top wall 3. Between the lining 18 and the top 3, is a flue 19 communicating with the oven through an opening 20 in the lining 18, and also communicating with an outlet pipe 21 at the rear of the stove.

55 Formed in the rear wall of the stove is an opening in which is mounted a tubular housing 22 which houses a fan 23 adapted to blow air forwardly through the oven. The fan is driven by a small electric motor 24 supported on a bracket 25 which is mounted on the rear wall of the stove. The fan housing has a front wall 26 provided with air ports 27. The passage of air through the fan housing is controlled by a valve 28, which is rotatably secured to the wall 26, and which is provided with apertures 29 adapted to register with the ports 27, when the valve is open. The valve is normally held in its closed position by a weight 30 mounted on the end of an arm 31 which is formed on one side of the valve. When the oven is used for baking, the valve is closed so as to prevent the escape of heated air through the fan housing, but when the improved heater is inserted into the oven, the valve is opened so as to admit air through the fan housing.

60 The heater includes an improved radiator which is adapted to be removably seated within the oven. In the forms shown, the radiator comprises a sheet metal housing having a top 32 and side walls 33. Formed at the rear end of the housing, is a rearwardly tapering header 34 having a tubular collar 35 adapted to surround the valve 28. The collar has a recess 36 for receiving the arm 31 of the valve. Mounted on this header 34 is a rearwardly projecting finger 37 having a cam edge 38 adapted to engage and lift the arm 31.

for automatically opening the valve when the radiator is inserted into the oven. The rear wall of the stove has a recess 39 for receiving this finger.

5 Mounted on the forward end of the radiator housing, is a plurality of horizontally disposed deflectors 40 which may be angularly adjustable if desired. The top and sides of the radiator housing have extensions 10 41 projecting beyond the deflectors.

Mounted on the sides of the radiator housing are flanges 42 which are adapted to slidably engage certain of the racks 12,7 for supporting the radiator. The flanges 42 are 15 preferably positioned so that the lower edges of the radiator walls 33 will slidably engage the oven bottom 11.

Mounted in the lower end of the radiator housing is a tube sheet 43 which is preferably of inverted cup shape to form a heater compartment 44 which is adapted to be placed directly above the burner, as shown in Figures 1 and 3.

The radiator also has a top header 45 25 which has an outlet pipe 46 projecting through the radiator top 32 for communication with the flue 19 through the opening 20. This header 45 is preferably spaced from the top 32 so as to permit the air stream to 30 engage both faces of the header, thereby increasing the efficiency of the radiator.

Communication between the two headers is provided by a plurality of vertically disposed flues which are spaced apart to define 35 air passages for the flow of air through the radiators. In the form shown in Figure 5, these flues consist of pipes 47 which are connected to the two headers.

In the preferred form shown in Figures 40 1, 2 and 3, the radiator has flues 48 of the same length and width as the side walls 33. These flues 48 are tapered rearwardly so as to define forwardly tapering air passages 49 between the flues. This type of core is highly 45 efficient.

In operation, when the stove is used for baking, the radiator is removed from the oven, and the cover plate 15 is placed over the opening 14. Upon withdrawal of the 50 radiator, the air valve 28 closes automatically.

When it is desired to use the stove as a heater, the plate 15 is removed and the radiator is inserted into the oven in the manner indicated. When the radiator is moved rearwardly, the cam 38 engages and lifts the valve arm 31. The burner is then ignited, and the fan is operated for forcing air forwardly through the radiator.

It will be understood that details of the 60 constructions shown may be altered without departing from the spirit of the invention as defined by the following claims.

I claim:

1. A stove comprising an oven having a bottom plate provided with an opening, a burner compartment below said oven, a burner in said compartment below said opening, a flue above said oven, a removable radiator located in said oven above said opening and having flues providing communication between said burner compartment and said first mentioned flue, and a fan for causing a flow of air through said radiator. 70 75

2. A bake oven having top, bottom, rear and side walls, a flue adjacent the top of said oven, said bottom wall having an opening, a burner adjacent said opening, a removable radiator located in said oven, said radiator comprising upper and lower headers and a plurality of intermediate flues, said lower header communicating with said opening, said upper header communicating with said oven flue, and means for causing a flow of air through said radiator. 80 85

3. A bake oven having top, bottom, rear and side walls, a flue adjacent the top of said oven, said bottom wall having an opening, 90 a burner adjacent said opening, a removable radiator located in said oven, said radiator comprising upper and lower headers and a plurality of intermediate flues, said lower header communicating with said opening, 95 said upper header communicating with said oven flue, said radiator flues being spaced apart to define air passages, and a fan for causing a flow of air through said air 100 passages. 100

4. A stove comprising an oven having a rear wall provided with an air port, a valve adapted to normally close said port, a portable radiator removably mounted in said oven, 105 said radiator having a part adapted to engage and open said valve, and a fan mounted adjacent said port for forcing air through said radiator. 115

5. A stove comprising an oven having a rear wall provided with an air port, a valve normally movable into position to close said port, a portable radiator removably mounted in said oven and having a part adapted to engage and open said valve, a motor mounted on said rear wall, and a fan driven by said motor and mounted adjacent said port for driving air through said radiator. 110 115

6. A stove comprising an oven having a pair of side walls, racks on said side walls, means for heating said oven, a portable radiator slidably mounted on said racks, and a fan at the rear of said oven for causing a flow of air through said radiator. 120 125

JESSE L. BRIGHT.
